SHIPPING CASE

Emil L. Herbolsheimer, Defiance, Ohio, assignor
to The Defiance Pressed Steel Company, De-
fiance, Ohio, a corporation of Ohio

Application April 26, 1933, Serial No. 668,089

9 Claims. (Cl. 220—73)

This invention relates to shipping cases which are primarily adapted for handling bottles or other articles of a similar nature.

According to the invention, the cases are constructed chiefly or wholly from metal, and the present construction has been devised primarily with the object of providing a case that will not become distorted or broken under the extremely rough handling to which such cases are often subjected. More specifically, the invention is concerned with novel and improved means for securing the bottom of the case to the side and end walls thereof and at the same time reinforcing the bottom flange member and the bottom corner connections against distortion, and providing means whereby the cases may be stacked one upon the other.

The detailed construction of the invention in its preferred form will be more particularly described in connection with the accompanying drawings, in which—

Figure 1 is an isometric view of an inverted case constructed according to the invention;

Figure 2 is a section taken on the line 2—2 of Figure 1;

Figure 3 is an isometric view of the rectangular frame which facilitates stacking;

Figure 4 is an isometric view of the bottom before it is attached;

Figure 5 is an enlarged sectional view taken on the line 5—5 of Figure 1.

As illustrated in the drawings, the case is formed with rectangular metallic side walls 10 and end walls 11, each of the latter being provided with a hand hole 12. The bottom is formed with side strips 13 connected by end strips 14, both the side and end strips being formed from sheet metal welded or otherwise suitably secured together at the corners. The opposite sides 13 are connected by transverse wires 15 on which the bottoms of the bottles rest. These wires 15 have laterally turned ends 16 anchored in beads 17 which are formed on the side strips by rolling the inner edge of each strip outwardly about the wire ends 16 and back upon itself as shown at 26. The interior construction which provides separate cells or compartments for the individual bottles is not shown since it does not constitute a part of the present invention.

The wires 15 are supported midway of their length by a longitudinal rib 18, which is also formed of sheet metal, bent upon itself, as shown at 27, the edge portions of the rib being turned outwardly to form shoulders 28 and then rolled to form beads 19, which constitute a central skid.

This skid is reinforced by a longitudinal strip 20 which is held between the inside edges of the beads 19 and the shoulders 28 and is welded at its ends to the end strips 14.

A stiff rectangular angle bar frame 21 embraces the beads 17 and the ends of the skids 18 and is secured to the edges 13 and 14 of the bottom. The vertical flange 22 of this angle bar frame is adapted to constitute a supporting base for the case or to be inserted in the top of an underlying case when stacking.

The side members 13 of the bottom are beveled at the ends and the transverse bottom members 14 have obliquely disposed ends 23 which are welded to the side members 13 adjacent their beveled ends, as shown in Figure 4. In attaching the bottom to the side and end walls, the latter are turned outwardly, as shown at 24. The bottom is then placed thereon and the edges of the side and end walls are folded about the edges of the strips 13 and 14, as shown at 25 in Figures 2 and 5. The angle bar frame 21 is then placed in position with its horizontal flange portion against the folded back edges 26 and the sides and ends of the case are then folded inwardly about the horizontal flange to complete the assembly. In this operation the overlapping portions 23 of the side and end strips 13 and 14 are securely interlocked, as will be evident from Figures 1 and 2. At the same time the angle bar frame 21 is securely locked between the folded edges 13 and the beads 17 and also between the folded edges 14 and the ends of the skids 19. The folding of the strips 14 also serves to strengthen the connection between the reinforcing members 20 and the ends 90 of the case.

By this construction the bottom is effectively secured to the side and end walls by interlocking seams which are folded about the flange of the angle bar frame and rigidly secure it. The interlocking seams also extend across the overlapping portions of the bottom strips, thereby diagonally reinforcing the corners. The manufacture of the case is therefore greatly simplified, and at the same time the greatest rigidity is secured for the bottom of the case and its connections with the side and end walls.

While I have shown and described specifically the preferred construction, it is apparent that the same may be considerably modified without departing from the scope of the invention as claimed.

What I claim is:

1. A shipping case comprising metallic side and end walls, a bottom, an angle bar frame adjacent

110

the edges of said bottom and formed with a peripheral flange, the bottom and the respective walls having interlocking seams folded about said flange, and a central bracing member extending 5 longitudinally across the bottom with its ends bound in said interlocking seams.

2. A shipping case comprising metallic side and end walls, a bottom having side and end strips, interlocking seams connecting the bottom strips 10 to the respective walls, wires extending across the bottom with their ends anchored to said strips, and an intermediate supporting member for said wires, said intermediate supporting member being bound at its ends in said interlocking 15 seams.

3. A shipping case comprising metallic side and end walls, a bottom having side and end strips welded together at the corners, said strips and the adjacent portions of said walls being 20 folded to form interlocking seams, the welded end of each strip extending across the fold line of the adjacent strip to form a diagonally reinforced corner connection.

4. A shipping case comprising metallic side and 25 end walls, a bottom having side and end strips overlapping at the corners, one of the overlapping ends being laterally beveled and the adjacent end of the other strip being disposed obliquely along the beveled end and welded thereto, said strips and the adjacent edges of the walls being 30 folded together to form interlocking seams which lock the walls to the strips and the ends of the latter to each other.

5. A shipping case comprising metallic side and 35 end walls, a bottom having side and end strips overlapping at the corners, extensions on the ends of one pair of said strips extending inwardly, interlocking seams connecting the bottom strips to the respective side and end walls whereby 40 said extensions are folded into the next adjacent sides of the case, and a reinforcing frame held by said interlocking seams.

6. A shipping case comprising metallic side and end walls, and a bottom having overlapping side and end strips, one pair of said strips having 45 parts extending obliquely inwardly from the ends thereof, so that upon folded interlocking of the side and end strips with the respective side and 50 end walls, the parts of one strip are received in the 55 interlocking seams of the other strip.

55

7. A shipping case comprising metallic side and end walls, a bottom having side and end strips, interlocking seams connecting the bottom strips to the respective side and end walls, and a central 60 bracing member extending longitudinally across the bottom with its ends bound in said interlocking seams.

65

8. A shipping case comprising metallic side and end walls, a bottom having side and end strips, interlocking seams connecting the bottom strips to the respective side and end walls, and a central 70 bracing member extending longitudinally across the bottom with its ends bound in said interlocking seams.

75

9. A shipping case comprising metallic side and end walls, a bottom having side and end strips, interlocking seams connecting the bottom strips to the respective side and end walls, and a central 80 bracing member extending longitudinally across the bottom with its ends bound in said interlocking seams.

end walls the extended portions of one pair of strips are received in the next adjacent walls.

7. A shipping case comprising metallic side and end walls, a bottom having side and end strips, interlocking seams connecting the bottom strips to the respective walls, wires extending across the bottom with their ends anchored to said strips, an intermediate supporting member for said wires comprising a U-shaped metallic strip having wire receiving openings in its bight portion and having its free ends bent outwardly to form shoulders and rolled back to form beads, and a reinforcing strip carried between the shoulders of said supporting member and the beaded parts thereof and having its ends fastened to the end strips and bound in said interlocking seams.

8. A shipping case comprising metallic side and end walls, a bottom having side and end strips, interlocking seams connecting the bottom strips to the respective walls, wires extending across the bottom with their ends anchored to said strips, an intermediate supporting member for said wires comprising a metallic strip doubled upon itself to form a rib, and flanged to form a channel portion, said rib portion being perforated to receive said wires, and a reinforcing strip in said channel portion fastened at its ends to said strips and bound in said interlocking seams.

9. A shipping case comprising metallic side and end walls, a bottom having overlapping side and end strips, one pair of said strips having parts extending obliquely inward from the ends thereof, so that upon folded interlocking of the side and end strips with the respective side and end walls 100 to form interlocking seams, the extended portions of one pair of said strips are received in the next adjacent walls, wires extending across the bottom and anchored in said strips, an intermediate supporting member for said wires comprising a metallic strip doubled upon itself to form a rib portion and flanged to form a channel portion, said rib portion being perforated to receive said wires, and a reinforcing strip in said channel portion fastened at its ends to said end strips and 105 bound in said interlocking seams.
